 corporation of Delaware

Application October 28, 1939, Serial No. 301,748

11 Claims. (Cl. 215—22)

This invention relates to improvements in bottle closures of the type utilized for preventing fraudulent refilling of bottles for profit.

The principal object of the invention resides in the provision of a structure for attachment to a bottle embodying valve means which are not only adapted when closed to seal the bottle in a liquid-tight manner, but which are at the same time adapted when the bottle is poured, to automatically function to relieve adventitious partial vacuums frequently occurring in bottles of this character during atmospheric temperature changes while corked, or otherwise sealed by the exceptionally tight seating of the valve means of this invention.

Another object of the invention is to obtain such functioning with a lesser number of moving parts than heretofore to thereby simplify, shorten, lighten and cheapen the closure.

The invention particularly consists of a duplex valve comprising two members, viz, primary and secondary elements, preferably loosely connected together, the former of which is utilized to open and close a relatively large inlet opening of the closure through which the liquid contents of the bottle is dispensed, and the other or secondary element of which is relied upon to open and close a relatively small air vent passing through the primary element and communicating with the interior of the bottle. The arrangement of these parts is such that it is only necessary to tilt the bottle into a pouring position in order to effect either the full opening of both valve members, or the precedence of the secondary member controlling the air vent should there be at that time a partial vacuum within the bottle. Following the equalization of air pressure conditions both valve members may then readily move together to permit free pouring, and in this instance without dependence upon any additional cooperating weighted means. Ordinarily the extent of such vacuums is comparatively slight and the aforesaid releasing of same is almost instantaneous, but the valve means disclosed herein is equally effective in releasing much higher vacuums, such as those occurring when the bottle is exposed to abrupt drops in atmospheric temperature during the winter season.

The initial opening of the secondary element of the valve mechanism while there is a partial vacuum in the bottle is made possible because of the extreme dissimilarity of the effective areas of the two valve members with respect to the openings they cover, and which permits the sec-

ondary element to release more readily under the same given pressure, and because of this principle the secondary element will function to release the aforesaid partial vacuums that otherwise would be quite strong enough over a larger area to hold the primary element seated and thus prevent the bottle from being poured.

The aforesaid valve mechanism is also designed to function in a like manner in the presence of abnormal vacuums which might be created artificially in the bottle to surreptitiously interfere with normal pouring of the contents, a somewhat greater time interval being then required for the equalization of the air pressure on opposite sides of the valve means, or such releasing may be augmented by a slight shaking of the bottle to hasten the desired separation of the valve members for the admission of air needed for this purpose. Generous clearances are provided to allow for ample freedom of movement of the secondary element in order that it may be capable of responding in this manner.

It will now be apparent that an important object of the invention is to provide a structure that will prevent any prolonged air locking of the bottle over an unreasonable period of time sufficient to condemn it for practical usage.

It will also be understood that means are provided herein for closing the air vent as well as the main inlet opening of the closure when an attempt is made to introduce liquid into the interior of the bottle and regardless of the position in which it may be held.

The invention will be more fully understood by reference to the drawing forming a part of this specification, and in which:

Figure 1 is a vertical section of the closure of this invention attached to a bottle top.

Figure 2 is a horizontal section through the closure on the line 2—2 of Figure 1 showing the secondary valve member in elevation.

Figure 3 is a similar view on the line 3—3 of Figure 1 showing the primary valve member in elevation.

Figure 4 is a side elevation of the primary valve member.

Figure 5 is a horizontal section through the closure on the line 5—5 of Figure 1 showing the guard member in elevation, and,

Figure 6 is a section similar to Figure 1 but shown inclined for pouring with the movable parts of the closure in another position in which the secondary valve member is now effective to

admit air, and just prior to the full opening of the entire valve means.

Referring now in detail to the drawing and more particularly to Figure 1, the top of a bottle neck is indicated at 10, to which is secured a closure assembly made up of a valve casing 11 having a valve seat 12 and an opening therethrough 13, a gasket 14, cover member 15, and valve mechanism comprising a duplex valve consisting of two members, 17 and 18, the former being hereinafter referred to as the primary element, and the latter as the secondary element, a spherical weight member 20, and a guard member 21. These parts are held in assembly with the bottle neck 10 by spinning the lower portion of a ferrule 19 in and around a suitable annular recess and bead formed in the glass.

The cover member 15, guard member 21 and valve casing 11 may be made of porcelain, or they may consist of moulded plastics of suitable character for contact with liquors contained in the bottle, and the guard member 21 may be secured in place by glazing the lugs 22 thereof to the inside walls of the cover member, or in the case of plastics, by cementing the same in place. A shoulder 23 formed within the cover member defines the relative position of the guard member with respect to proper clearances for the egress of liquid above lugs 22, and spaces 22' shown in Figure 5 between the lugs, are for the same purpose. The spherical weight member 20 is preferably made of glass or agate because of its suitability for this purpose. The valve seat 12 is of a particular configuration consisting in cross section, as shown in Figure 1, of a segment of a sphere the full size of which latter being indicated in broken lines, and extends upwardly from the bottom inside surface of member 11.

The purpose of the weight member 20 and the cooperating inclined inside walls of the guard member 21 has been fully described in our co-pending application, Ser. No. 298,900 filed October 11, 1939, as has also the gasket 14 for providing an airtight joint with the bottle top, and this specification will therefore be largely confined to the novel valve means shown herein.

The primary element 17 of the said valve means is preferably made of moulded plastic material and is light in weight. It has a disk-shaped base 24 provided with a plurality of guiding and supporting lugs 25 geometrically spaced apart to provide passageways 25' for the egress of liquid, as shown in Figure 3, and extending radially outwardly toward the inner surrounding walls of the valve casing 11 from which they are suitably spaced to provide ample clearance for free movement of element 17 axially of the bottle within said casing. The lower surface of the base 24 is recessed at 26 to provide an annular surface 26' of frusto-conical configuration with an angle of substantially 45 degrees, for engagement with the valve seat 12, there being substantially a line contact to thus provide a tight joint when element 17 is seated, which is fully resistant to low as well as high pressures that may be used in attempts to defeat the purpose of the invention, and without the necessity of expensive grinding or lapping of one surface to the other. The corners of the lugs 25 are rounded as shown to facilitate such axial movement of element 17, and so that the same may rock universally to a limited extent upon seat 12 without leaving it.

Element 17 is provided with an upwardly projecting member 27 frusto-conical in shape externally, with an angle of substantially 45 degrees, 75

and terminating in a cylindrical tip 28 the top surface 29 of which is spherical. The inside of member 27 is recessed at 30 directly above recess 26, and an air vent 31 leads from same through the tip 28. As the air vent 31 has a diameter of only .040" it is of extremely small area compared to that of the valve seat opening 13, the latter being $\frac{7}{16}$ " in diameter.

Element 18 is also preferably made of moulded plastic material, such as is known to the trade as polystyrene, and which is appropriate for use in contact with distilled liquors. Element 18 is therefore light in weight like element 17 because the principles used in effecting the pouring of the bottle closure of this invention do not involve heavy valves or separate weighted means adapted to adhere to the valve means when wet, but instead deal primarily with the admission of air to compensate for partial vacuums within the bottle, or those about to form above the liquid contents when a full bottle is inverted and some of its contents starts to enter the closure.

Element 18 is hollow so that it will float, and is sufficiently buoyant to also effect the flotation of element 17 when the bottle is in an inverted position, or otherwise inclined so that the valve seat 12 is far enough below a horizontal plane to render the spherical weight member 20 ineffective to move the valve elements toward said seat. Element 18 consists of two members 35 and 36 secured together in an airtight manner to form a hollow float. The member 35 is hollow, generally cylindrical, and open at the top to snugly receive an annular flange 37 extending downwardly from the flat disk-like cover member 36 to provide a press fit joint which may be sealed if necessary by the use of a proper adhesive, so that there can be no leakage of liquid into the interior of the element. Member 35 has a hollow projection 38 extending upwardly from its base and forming an integral part thereof. The lower annular walls 38' of projection 38 correspond in shape to that of member 27 of element 17, and taper inwardly and upwardly terminating in a spherical configuration as at 39, of slightly greater radius than that of the tip 28 of element 17 upon which said spherical surface is adapted to seat and form a substantially airtight joint to seal the air vent 31.

It will be noted that there is substantially a line contact between these engaging surfaces which closely coincides with the circle defined by the intersection of the top edge of the vent 31 and the surface 29 of tip 28. In this manner the effective area of the said joint approximates that of the vent to minimize the suction of the aforesaid vacuums at this particular place. It will be apparent that element 18 is supported on the tip 28 when the bottle is upright, and consequently is free to rock universally on same without uncovering the vent 31. The upwardly extending tip 28 of element 17 provides for ample clearances for this purpose between the inner walls 38' of projection 38 and the outer walls of member 27 of element 17, and to also prevent the formation of adhering films of liquid therebetween tending to obstruct the free passage of air to vent 31 when desired, and to furthermore ensure the ready separation of elements 17 and 18 when needed for the purpose set forth.

Cover member 36 is provided with a plurality of circumferentially disposed lugs 40 extending radially outwardly therefrom. Ample clearance is allowed between the same and the adjacent walls of the valve casing 11 to permit element 18 to partake of the aforesaid rocking movement,

the purpose of which will presently appear, and also to provide passageways 41 between said lugs for the egress of liquid, as shown in Figure 2.

Projection 38 terminates in a cylindrical tip 42 the top of which is spaced from the cover member 36, and is provided with a through-opening 43 axially thereof for the tight reception of a pin 44 extending downwardly through the air vent 31. The head 45 of the pin 44 is spaced from the lower end of vent 31 to permit relative movement of elements 17 and 18 so that when the bottle is inverted element 18 may move first to open the vent 31, and then pick up element 17 by means of the engagement therewith of the head 45 of the pin 44. In this way the weight 15 of element 18 is added to that of element 17 to assist in unseating the latter, and to maintain the same in an unseated position so as to prevent danger of possible undesirable reseating due to the natural suction of replacement air entering the bottle during the pouring of same. The other end of pin 44 extends beyond the tip 42 of projection 38, and may be enlarged as shown at 46 by pinching, to prevent accidental withdrawal.

It will be understood that the assembly of elements 17 and 18 with the pin 44 is effected prior to the assembly of the cover member 36. If required a suitable adhesive may be applied to seal the pin within the opening 43 in an airtight manner so that no liquid may find its way into the air chamber of element 18.

The releasing action of element 18 is equally effective without the use of the pin 44, but a full bottle when inverted will then not break open 35 to pour automatically but has to be tilted quickly, or given a shake in order to unseat element 17. Pin 44 is preferably heavily tinned to protect against any contamination of the liquor.

It is believed the parts first assume the position shown in Figure 6 as the bottle is inclined to begin pouring. It will be seen that element 18 has tipped and moved forwardly and that the vent 31 is now uncovered so that any climatic or artificial vacuum may be relieved, and element 17 be unseated, the valve means then being free to move on to a fully open position with the cover member 36 contacting the weight member 20 now in the pocket formed in the guard.

After the bottle is empty and again inverted to reopen the valve means, any entering liquid will at once float element 18 into engagement with the tip 28 of element 17, and consequently the vent 31 will be closed. As the liquid rises, as by the use of pressure, element 18 through forces of buoyancy will carry element 17 into a seated position. In any other positions of the bottle approaching a horizontal plane the weight member 20, through forces of gravity acting on the inclined walls of guard 21, will push both valve elements into their respective seating positions. When the bottle is upright weight member 20 will hold both valve elements in such position, and any attempt to unseat them, as by agitation, will largely result in the movement of the weight member alone because of the extreme lightness of the valve elements and the forces of adhesion present between element 17 and seat 12.

It is also believed that the absence of longitudinal ribs inside of the valve casing 11, such as those shown in our co-pending application above referred to, and the substitution therefor of the lugs 25 and 40 respectively on elements 17 and 18, with each group relatively remote from the

other, results in a greater flexibility of the valve means with respect to the separation of the primary and secondary elements thereof in the desired releasing operation. Such freedom of movement pivotally about the tip 28 is aided by the clearances between the contiguous surfaces of member 27 and the projection 38. In other words, both elements are loosely joined and loosely housed for the promotion of easy angling with respect to each other, and which characteristic appears to unquestionably enhance the desired releasing functioning without loss of protection against refilling.

The releasing operation of element 18 is timed to be in advance of the pouring of the bottle. This result is obtained by placing the center of gravity of element 18 beyond its center of suspension on element 17 when the bottle is in a horizontal position, so that the tipping or rocking movement of element 18 to uncover the air vent 31 can occur before the normal pouring angle of the bottle is reached. However, on the other hand, when any attempt is made to refill the bottle with element 18 in such vacuum releasing position, as by the use of pressure when element 17 may be held to its seat by adhesion, the secondary element 18 will then be moved by forces of buoyancy, set up by the entering liquid, into a seated position before said liquid can enter the bottle through the vent 31, because the metacenter of element 18 is also forward of its point of suspension on element 17 which causes it to be more immediately responsive to such forces.

Furthermore, when the bottle is in the position illustrated in Figure 6, but now with both valve elements in an open pouring position in which the vent 31 will be incidentally closed because element 17 will have been swept into its extreme open position by the outflowing liquid, and under which circumstances the lugs 25 and 40 will be resting against the lower inside wall of the casing 11, the axis of the valve means will be angularly disposed with respect to the axis of the closure, 45 due to the lugs 40 being radially shorter than the lugs 25. If liquid is now introduced for the purpose of refilling the bottle with the latter restored to a flatter position but one in which the weight member 20 is still ineffective to close the valve means, the metacenter of the valve means in its entirety will now substantially coincide with the center of gravity thereof, and both elements of the valve means will then be in a state of buoyant equilibrium, with the said axis of the 50 valve means in substantial alignment with the axis of the closure. While the valve means is in such state of equilibrium it will readily float toward the valve seat 12 along a rising inclined plane substantially parallel to the axis of the closure, and with a consequent minimizing of friction or cramping tending to interfere with such freedom of movement.

The words "beyond" and "forward" are intended to refer to a direction axially of the bottle 65 away from the valve seat 12, and toward the cover member 15.

What is claimed is:

1. In a closure of the kind described for attachment to a bottle, and having a valve compartment provided with inlet and outlet openings at the opposite ends thereof respectively, and a valve seat surrounding said inlet opening, valve mechanism and separate cooperating weighted means, both movable in said compartment, the former consisting of a primary element and a

secondary element, said primary element being adapted to engage said seat and close said inlet opening, and having an air vent therethrough of relatively small area with respect to that of said inlet opening, and said secondary element having a part adapted to close said vent, and means for loosely coupling the secondary element to said primary element adapted when the bottle is inverted toward a pouring position to provide for a limited relative movement of these elements to uncover said air vent for the purpose set forth, said relative movement being effective independently of any connection to said separate weighted means.

2. The structure set forth in claim 1, in which the secondary element of the valve means is buoyant and capable of also floating the primary element.

3. In a closure of the kind described for attachment to a bottle, and having a valve casing provided with inlet and outlet openings at the opposite ends thereof, and a valve seat, valve mechanism movable in said casing comprising a primary element and a secondary element loosely connected together, said primary element being adapted to engage said seat and close said inlet opening, and having an air vent therethrough of relatively small area with respect to that of said inlet opening, and said secondary element having a part adapted to close said vent, each 30 of said elements having a plurality of annular lugs projecting radially therefrom at the opposed ends thereof so that the lugs on one element will be remote from those on the other element axially of said closure, and said lugs being adapted 35 to guide and support said elements in cooperation with the adjacent surrounding walls of said casing, the loose connection comprising an enlarged outer end on a part of one of the valve elements of greater diameter than an opening in the other valve element through which it is adapted to extend.

4. The combination set forth in claim 3, in which the extremity of the lugs of the secondary element defines a circle the diameter of which is less than that of a circle similarly defining the lugs of the primary element, and in which the center of gravity of the secondary element, when the bottle is moved from an upright to a horizontal position and the valve elements are seated, 50 will be beyond its said center of suspension on the primary element, to thereby effect the tipping of the secondary element to uncover the said air vent before the normal pouring angle of the bottle is reached.

5. The combination set forth in claim 3, in which there are means for effecting the flotation of the secondary element when the bottle is inverted at an angle close to the horizontal, and in which the metacenter of the secondary element, 60 including said means, is forward of its point of suspension on the primary element for the purpose set forth.

6. The combination set forth in claim 3, in which the metacenter and the center of gravity 65 of the valve mechanism substantially coincide when the bottle is restored from a pouring position to one approaching the horizontal, whereby the said valve mechanism will then be in substantially buoyant equilibrium and capable of 70 floating toward said valve seat in substantially coaxial alignment with said closure for the purpose set forth.

7. The combination set forth in claim 3, in which said valve seat projects upwardly from the 75

base of said casing and corresponds in shape to the segment of a sphere, and in which the primary element of the valve mechanism consists of a disk having said lugs on the periphery thereof, 5 and having a tapered projection extending upwardly therefrom terminating in a cylindrical tip the top of which corresponds in shape to the segment of a sphere, the face of said disk adjacent said valve seat being recessed with a frusto-conical configuration to provide inclined annular walls for engagement with said valve seat with substantially a line contact, and in which the secondary element of said valve mechanism comprises a hollow cylindrical body member open at one end, and a flat cover member adapted to close said open end to provide a float with an air chamber, said cover member having said lugs on the periphery thereof, and having a projection extending upwardly within said air chamber 15 from the base of said body member having a recess in the lower face thereof adjacent said primary element of frusto-conical configuration to provide annular inclined walls, and which merge into a spherical top surface for engagement of the latter with the top surface of the cylindrical tip of said tapered projection of the primary element.

8. The combination set forth in claim 3, in which the said valve seat projects upwardly from the base of said casing and corresponds in shape to the segment of a sphere, and in which the primary element of the valve mechanism consists of a disk having said lugs on the periphery thereof, and having a tapered projection extending upwardly therefrom terminating in a cylindrical tip the top surface of which corresponds in shape to the segment of a sphere for engagement with a surface on said secondary element to close said air vent, the face of said disk adjacent said valve seat being recessed and of a frusto-conical configuration to provide inclined annular walls for engagement with said valve seat with substantially a line contact.

9. The combination set forth in claim 3, in which the secondary element of the valve mechanism comprises a hollow cylindrical body member open at one end, and a flat cover member adapted to close said open end to provide a float with an air chamber, said cover member having said lugs on the periphery thereof, and having a projection extending upwardly within said air chamber from the base of said body member having a recess in the lower face thereof adjacent said primary element of frusto-conical configuration to provide annular inclined walls and which merge into a spherical top surface for engagement of the latter with a surface on said primary element to effect the closing of said air vent.

10. The structure set forth in claim 1, in which the means provided for loosely coupling said elements includes a part thereof operative to effect an engagement of said elements following said relative movement, and so that the weight of the secondary element will supplement that of the primary element to thereby assist in unseating the latter to pour the bottle.

11. In a closure of the kind described for attachment to a bottle, and having a valve compartment provided with inlet and outlet openings at opposite ends thereof respectively, and a valve seat surrounding the inlet opening, valve means movable in said compartment comprising a primary element, and a secondary element normally supported on the primary element, a projection

on one element, and the other element having a recess for the reception therein of said projection, the primary element being adapted to engage said valve seat and close said inlet opening, and having an air-vent opening therethrough leading from said compartment to said inlet opening, and the secondary element being adapted to close said air-vent opening, and said recess and projection having engageable seating surfaces effective for sealing said air-vent opening, and of a configuration that the secondary element is free to gyrate on the primary element

5 about the geometric axis of the closure without uncovering said air-vent opening, and the said valve seat and the face of the primary element being also of a configuration that the primary element is free to gyrate upon said valve seat in a similar manner without uncovering said inlet opening, and coupling means arranged to loosely connect the valve elements so that they can separate to a predetermined extent comprising an element passing through said air-vent opening.

EDGEWORTH GREENE.
WILLIAM H. FORREST.
